UNITED STATES PATENT OFFICE

2,661,772

SWORD WITH REMOVABLE PROTECTOR
ROD BRACKETSJesse B. Goodgame, Charlotte, N. C., assignor to
Precision Gear and Machine Company, Charlotte, N. C., a corporation of North Carolina

Application December 19, 1952, Serial No. 326,953

6 Claims. (Cl. 139—1)

1

This invention relates to looms for weaving fabrics and more especially to improved lay swords having removable protector rod support brackets thereon.

Conventional swords associated with most looms each has a pair of spaced ears disposed immediately rearward of the lay and through which a pivot pin extends on which the front end of a pitman arm is pivotally mounted. Also, heretofore, each of the swords has had a protector rod support bearing portion integral therewith which was substantially L-shaped in cross-section and the vertical leg of which engaged the rear surface of the lay and the horizontal leg of which engaged the lower surface of the lay for supporting said lay. Also, the horizontal leg of each of the protector rod bearing portions has had a projection extending downwardly therefrom, or said horizontal leg has been in the form of such a projection, in which the conventional protector rod was oscillatably supported.

As is well known, the protector rod has daggers on opposite ends thereof which are raised in the course of each forward or beat-up stroke of the lay when a shuttle is properly boxed in either of the shuttle boxes. On the other hand, upon failure of the shuttle to be properly boxed in either of the shuttle boxes, in the course of a beat-up stroke of the lay, the daggers remain in a lowered position and then engage frogs which restrain forward movement of the lay and also actuate conventional means for stopping the loom.

Now, heretofore, relative pivotal movement has been caused between the swords and the pitman arm pivot shafts and/or the front ends of the pitman arms and the pitman arm pivot shafts. Also, the protector rod has oscillated, either in direct contact with the projections extending downwardly from the protector rod support brackets or in friction bearings disposed in said projections, thus resulting in considerable wear of the pitman arm pivot shafts and the protector rod as well as the portions of the swords and/or pitman arms and the projections on the protector rod supporting brackets with which they were in engagement.

It is therefore an object of this invention to provide anti-friction bearings in the ears of the swords for pivotally supporting the pitman arm pivot shaft and to also provide anti-friction bearings in the protector rod brackets for oscillatably supporting the protector rod.

More especially, it is an object of this invention to provide swords especially constructed to

2

facilitate adaptation thereof for the reception of the above anti-friction bearings and, to this end, I have provided swords each including a shank having laterally spaced ears thereon and a protector rod support bracket detachably secured thereto and extending outwardly therefrom whereby the protector rod support bracket may be removed from the sword shank to facilitate machining the openings in the ears of the swords for reception of anti-friction bearings, since it is extremely difficult to accurately machine the openings for said anti-friction bearings in the ears of the swords when the corresponding protector rod support brackets are cast integral with the shanks of the swords.

Moreover, by constructing the protector rod support brackets as parts separate from the sword shanks, this facilitates the machining of openings in the projections extending downwardly from the protector rod support brackets for the reception of anti-friction, preferably self-aligning and sealed bearings.

It would be practically impossible to accurately machine the openings in the projections extending downwardly from the horizontal legs of the protector rod brackets if the protector rod brackets were integral parts of the sword shanks, since said projections are spaced substantially from the innermost surfaces of the swords and are spaced inwardly substantially from the outermost or end portions of the brackets, with the result that the cutting and abrading tools employed in machining the openings in said projections would have to be so long that the working ends thereof could not be sufficiently rigidly supported in order to maintain the diameters of said openings within the relatively close tolerances necessary to accommodate anti-friction bearings.

In any event, by providing a detachable protector rod support bracket on each of the swords, many of the operations necessary in the manufacture of the sword shanks and the protector rod brackets are greatly simplified, since the sword shanks and protector rod brackets are not as cumbersome to handle when manufactured separately; they are more easily and more accurately molded and, since the protector rod support brackets are not integral parts of the sword shanks, this obviates the possibility of the protector rod brackets becoming broken away from the swords due to handling in the process of their manufacture, as is so often the case in handling cast iron parts having elongated protuberances thereon of relatively small cross-sectional area.

Some of the objects of the invention having been stated, other objects will appear as the description proceeds, when taken in connection with the accompanying drawings, in which—

Figure 1 is a fragmentary top plan view of a loom with the central portion broken away and many of the parts omitted and showing the improved multisection swords in association therewith;

Figure 2 is an enlarged fragmentary rear elevation, with parts in section, taken substantially along the line 2—2 in Figure 1;

Figure 3 is a fragmentary vertical sectional view of the loom taken substantially along the line 3—3 in Figure 1;

Figure 4 is an enlarged fragmentary vertical sectional view taken substantially along the line 4—4 in Figure 2;

Figure 5 is an enlarged fragmentary sectional plan view taken substantially along the line 5—5 in Figure 4;

Figure 6 is an enlarged fragmentary isometric view showing the upper end of one of the sword shanks with the corresponding protector rod bracket fixed thereon;

Figure 7 is a view similar to Figure 6, but showing the sword shank and corresponding protector rod bracket at the opposite side of the loom;

Figure 8 is an enlarged fragmentary vertical sectional view taken substantially along the line 8—8 in Figure 2.

Referring more specifically to the drawings, the numerals 10 and 11 indicate the right-hand and left-hand frame members of a loom. The front upper ends of the side frame members 10 and 11 have opposite ends of a conventional breast beam 12 suitably secured thereto and the medial portions of the side frame members 10 and 11 have opposite ends of a suitable girt or spreader 13 suitably secured thereto. This spreader 13 may be of any desired or conventional construction and is preferably of the type disclosed in my co-pending application entitled Adjustable Spreader for Looms, Serial No. 326,951, filed December 19, 1952.

Spaced below the spreader or girt 13 is a conventional driven crank shaft 14 on which pick cams 15 are suitably secured, only one of which is shown in Figure 3. The pick cams 15 each engage a pick ball 16 for controlling the movement of the conventional picker sticks, not shown. Of course, the side frame members 10 and 11 support the usual warp beam 20 from whence warp yarns pass upwardly above the girt or spreader 13, through suitable harnesses, not shown, and through a reed 21 where the fabric is formed. The fabric is taken up by a conventional sand roll 22 rotatably supported in the side frame members 10 and 11 and which usually has a cloth take-up mechanism associated therewith, not shown.

The reed 21 is disposed between a reed cap 24 and a lay 25 which are supported by improved swords 30 and 30' which are especially constructed according to the present invention and will be later described in detail. The lower ends of the swords 30 and 30' are fixed on a conventional rocket shaft 30a oscillatably mounted in the side frame members 10 and 11.

Front end cuff members 31 and 31' are pivotally connected to the respective swords 30 and 30', in a manner to be later described, these cuff members 31 and 31' being conventional parts of pitman arms 32 and 32'. The rear ends of the

pitman arms 32 and 32' are pivotally connected, as at 33 and 33', to respective crank throws 34 and 34' of a crankshaft broadly designated at 35.

The crankshaft 35 may be of any desired or conventional construction, but is preferably of the type disclosed in my co-pending application entitled Multisection Crankshaft for Looms, Serial No. 326,952, filed December 19, 1952. Accordingly, the medial portion of the crankshaft 35 is rotatably mounted in a pair of inboard bearing blocks 36 and 36' suitably secured to the upper surface of the girt or spreader 13 and the outer ends of the crankshaft 35 are rotatably mounted in outboard bearing blocks 37 and 37'.

As is well known, most automatic looms have an automatic bobbin transfer mechanism and opposite ends of the lay 25 have shuttle boxes 40 and 40' thereon provided with stationary box fronts 41 and 41' and stationary longitudinally slotted box backs 42 and 42' in the slots of which conventional box binders are positioned and which are adapted to be engaged by a shuttle S as it is alternately boxed in the shuttle boxes 40 and 40'. Only one of said box binders is partially shown and is indicated at 43' in Figures 1, 2 and 8.

It will be observed in Figure 8 that the front portion of the lay 25 is cut away at 44, in the usual manner, beneath the shuttle box 40' and this cutaway portion 44 is partially covered or closed by a shuttle box bottom plate 45' provided with a longitudinally extending slot 46 therein through which the exhausted bobbins are discharged and then pass through the opening 44. Disposed in the opening 44 and extending downwardly substantially below the lay 25 is an inclined bobbin chute or picker stick guide 47 which is conventional and is only described since one of the improved protector rod support brackets has means thereon for supporting the bobbin chute or picker stick guide 47, as will be later described.

The loom is also equipped with a protector rod 50 which is oscillatably supported adjacent the swords 30 and 30' in an improved manner, to be later described, and is also supported in an intermediate or center protector rod bracket 51 which preferably has an anti-friction bearing therein for oscillatably supporting the rod 50. This center protector rod bracket or bearing block 51 is suitably secured, as by a screw 52, to the medial portion of the lay 25. The bracket or bearing block 51 has one end of a torsion spring 53 suitably connected thereto which surrounds the adjacent portion of the protector rod 50 and the other end of which is fixed to a collar 55 fixedly mounted on the protector rod 50.

Opposite ends of the protector rod 50 have outwardly and rearwardly bent or turned portions 56 and 56' integral therewith on which the lower ends of respective dagger fingers 57 and 57' are suitably secured. These dagger fingers 57 and 57' extend upwardly and engage the corresponding box binders, only one of which is partially shown and is indicated at 43', normally tending to move the binders inwardly or forwardly by virtue of the torsion spring 53.

Opposite ends of the protector rod each has a dagger fixed thereon and extending downwardly and forwardly therefrom, only one of said daggers being shown and indicated at 60' in Figures 2, 3 and 8. The torsion spring 53 normally urges each of the daggers, such as dagger 60', downwardly into the horizontal plane of a

protuberance 61 on a corresponding frog 62 carried by the corresponding side frame members 10 and 11. As is well known, most looms have two frogs thereon, as above described, one of which is termed a live frog and the other of which is termed a dead frog and the live frog is effective in stopping the loom upon the protuberance thereon being engaged by the corresponding dagger to limit forward movement of the lay 25. Since the structure and function of the live frog and dead frog associated with looms is well known, further illustration and description thereof is deemed unnecessary.

All of the parts heretofore described, other than the swords 30 and 30', are conventional and the present invention is concerned with improvements embodied in the swords 30 and 30'. Since both of the swords 30 and 30' are substantially the same, only the sword 30 will be described in detail and like parts associated with the sword 30' will bear the same reference characters with the prime notation added.

As heretofore stated, the primary object of the invention is to provide means facilitating the use of antifriction bearings in association with the swords for supporting the front ends of the pitman arms and for oscillatably supporting the protector rod 50. The sword 30 comprises a substantially vertical shank 64 which has laterally spaced, rearwardly projecting inner and outer ears 65 and 66 integral therewith and is provided with an outer flat vertical surface 67 which is flush with the external surface of the ear 66 and forms a shoulder 68 on the shank against which a vertical end flange portion 70 of an improved protector rod support bracket, broadly designated at 71, is adapted to be detachably secured, as by screws 72 (Figures 2, 4 and 6).

Heretofore, a bracket similar to the bracket 71 has been cast or molded integral with the shank 64 of the sword 30. The improved protector rod support bracket 71 is made so as to be removed from the shank 64 to facilitate accurately machining the ears 65 and 66 as well as a bearing holding projection 73 which projects forwardly from the lower portion of the flange portion 70 of the improved protector rod support bracket 71.

It will be observed in Figures 5 and 6 that the ears 65 and 66 each has a relatively large bore 75 therein, these bores 75 being axially aligned and the inner or proximal ends of the bores 75 being restricted to form shoulders 76 against which the outer races of respective anti-friction bearings 80 are positioned. The anti-friction bearings 80 are illustrated as ball bearings in Figure 5, however, it is to be understood that roller bearings may be employed in lieu of the ball bearings, if desired. The ball bearings 80 are preferably held in the bores 75 in the ears 65 and 66 by a light pressed fit.

The reduced opposite ends 81 of a pitman arm front pivot shaft 82 fit in the inner races of the anti-friction bearings 80 and the front end portion 31 of the corresponding pitman arm 32 is mounted on the medial portion of the shaft 82 between the ears 65 and 66, and is held thereon by means of a set screw 83.

It is thus seen that there is no frictional contact between the reduced ends 81 of the pitman arm pivot shaft 82 and the ears 65 and 66, as has heretofore been the case, and, thus, the pitman arms 32 and 32' operate quieter than pitman arms heretofore employed and the ears

65, 66, 65' and 66' are not worn as a result of oscillation of the pivot shafts 82 and 82' therein.

It will be observed in Figures 2, 4, 5, 6 and 7 that the protector rod brackets 71 and 71' are provided with respective vertical web portions 84 and 84' which extend outwardly and whose front faces are substantially flush with the front faces of the respective sword shanks 64 and 64' and are adapted to be positioned against the rear surface of the lay 25. The respective bearing holding projections 73 and 73' extend forwardly from the lower portions of the respective flanges 70 and 70' and are substantially circular and provided with respective substantially flat planar upper surfaces 85 and 85'. Thus, the lay 25 is supported upon the flat surfaces 85 and 85' of the respective bearing holding projections 73 and 73' and the rear surface of the lay 25 is held against the web portions 84 and 84' by respective bolts or screws 86 and 86' (Figure 2). These bolts 86 and 86' are preferably of the shouldered type and, accordingly, the web portions 84 and 84' of the respective brackets 71 and 71' are provided with respective rectangular holes 87 and 87' through which the shoulder bolts extend for securing the lay to the brackets 71 and 71'.

Since the bores or openings in the ears 65, 66, 65' and 66' are necessarily disposed in close proximity to the rear surfaces of the sword shanks 64 and 64', it is preferable that the flanges 70 and 70' of the respective brackets 71 and 71' have substantially semi-circular notches or cavities 90 and 90' therein which are disposed in axial alignment with the bores or openings 75 and 75' in the ears 65 and 66'. These notches 90 and 90' are also preferably of slightly greater radius than the radii of the bores 75 and 75' in order to facilitate ready removal of the anti-friction bearings 80 and 80' from the ears 65 and 66' without detaching the bracket 71 and 71' from the shanks 64 and 64' of the swords 30 and 30', if desired.

The bearing holding projections 73 and 73' have respective axially aligned bores 91 and 91' therein and each of the bores 91 and 91' has the outer race of an anti-friction bearing 92 mounted therein (Figures 4 and 5). These anti-friction bearings 92 are preferably of the self-aligning type as shown in Figure 5 and the protector rod 50 slidably penetrates the inner races of the anti-friction bearings 92.

The inner race of each of the anti-friction bearings 92 preferably has a tapered end portion indicated at 93 for reception of a correspondingly tapered portion of a collar 94 which is fixed on the protector rod 50 by means of a set screw 95. The anti-friction bearings 92 may be either roller bearings or ball bearings and are also preferably sealed bearings, between the inner and outer races of which a suitable lubricant has been provided by the manufacturer to thereby obviate the necessity of providing means for lubricating the bearings 92.

Now, it will be observed in Figure 7 that the web portion 84' of bracket 71' is substantially longer than the web portion 84 of bracket 71 and the outer portion of the web portion 84' has a horizontal flange portion 97 projecting forwardly from the lower edge thereof which is disposed at substantially the same level as the flat surface 85' on the upper edge of the bearing holding projection 73'. The lower surface of this flange portion 97 has a boss 100 integral therewith which is provided with a bore 101 for reception of a bolt 102 for securing the inclined bobbin.

chute or picker stick guide 47 to the front surface of the bracket 71'.

It is thus seen that I have provided an improved combination lay sword and protector rod bracket wherein the protector rod bracket is formed separately from the shank of the sword to facilitate accurate machining of the bores 91 and 91' in the bearing holding portions 73 and 73' of the respective brackets 71 and 71' and to also facilitate ease of handling the swords 30 and 30' and machining the bores 75 and 75' in the respective pairs of ears 65, 66 and 65', 66' so that anti-friction bearings may be used for supporting the protector rod 53 and for supporting the pitman arm front end pivot shafts 82 and 82'.

In the drawings and specification there has been set forth a preferred embodiment of the invention and, although specific terms are employed, they are used in a generic and descriptive sense only, and not for purposes of limitation, the scope of the invention being defined in the claims.

I claim:

1. In a loom having a lay and a pair of pitman arms, a pivot shaft on the front end of each pitman arm, a protector rod extending beneath, and substantially parallel to, said lay, and swords for supporting the lay each having a pair of spaced ears thereon between which the front ends of said pitman arms are adapted to fit; the combination of a flat outer surface on each of said swords adjacent the corresponding ear, a detachable protector rod bracket removably secured to said flat surface on each sword, each protector rod bracket having a bearing holding projection thereon projecting in a direction away from the corresponding ear of the sword and disposed beneath said lay for supporting the corresponding portion of the lay, each of said ears and the bearing holding projections having a bore therein, and an anti-friction bearing mounted in each of said bores for oscillatably supporting said protector rod and said pitman arm pivot shaft.

2. In a loom having a lay, pitman arms for driving the lay and a protector rod extending beneath, and substantially parallel to, said lay; improved swords for supporting the lay, each sword comprising a shank having a pair of laterally spaced ears thereon, an anti-friction bearing in each of said ears, a pivot shaft mounted in the bearings and spanning the distance between each pair of ears and on which the front end of the corresponding pitman arm is adapted to be secured, a protector rod bracket removably secured to the outer surface of each of said shanks, each protector rod bracket comprising a substantially vertical web portion, means securing the lay to the web portion of each bracket, a bearing holding projection extending forwardly from the lower portion of each of the web portions and beneath said lay, and an anti-friction bearing mounted in said bearing holding projection on each of the protector rod brackets for oscillatably supporting said protector rod.

3. An improved combination sword and protector rod bracket for supporting the opposite end portions of a lay of a loom and for also supporting the protector rod of the loom, said loom also having a pair of pitman arms thereon for imparting oscillation to said lay; each of said improved combination swords and protector rod brackets comprising a sword shank having a pair of laterally spaced ears thereon between

which the front end of the corresponding pitman arm is adapted to fit, an anti-friction bearing mounted in each of said ears, a pivot shaft oscillatably mounted in the bearings in each of said 5 pairs of ears and on which the corresponding pitman arm is adapted to be fixedly mounted, a bracket removably secured to the outer surface of each sword shank adjacent the corresponding pair of ears, an outwardly extending substantially vertical web portion integral with each bracket and having means for securing the lay thereto, each bracket also having a projection extending forwardly therefrom beneath said lay and being disposed at the end of said bracket 10 adjacent the corresponding sword shank, and an anti-friction bearing mounted in said projection on each of the brackets for oscillatably supporting said protector rod.

4. In a loom having oscillatable swords and a 20 lay disposed against the front surfaces of the swords; the combination of a detachable bracket fixed to the outer surface of each sword and having an outwardly projecting substantially vertical web portion thereon whose front surface is substantially flush with the front surface of the sword, means to secure the lay to said web portion, and a forwardly extending projection on each bracket upon which the lay is adapted to rest.

5. An improved combination sword and 30 protector rod bracket for supporting the opposite end portions of a lay of a loom and for also supporting the protector rod of the loom, said loom also having a pair of pitman arms thereon for imparting oscillation to said lay and an inclined bobbin chute disposed at at least one end of the lay; each of said improved combination swords and protector rod brackets comprising a sword shank having a pair of laterally spaced ears

40 thereon between which the front end of the corresponding pitman arm is adapted to fit, an anti-friction bearing mounted in each of said ears, a pivot shaft oscillatably mounted in the bearings in each of said pairs of ears and on which the 45 corresponding pitman arm is adapted to be fixedly mounted, a bracket removably secured to the outer surface of each sword shank adjacent the corresponding pair of ears, an outwardly extending substantially vertical web portion integral with each bracket and having means for securing the lay thereto, each bracket also having a projection extending forwardly therefrom beneath said lay and being disposed at the end of said bracket adjacent the corresponding sword

50 shank, an anti-friction bearing mounted in said projection on each of the brackets for oscillatably supporting said protector rod, at least one of said brackets also having a forwardly projecting flange portion integral with the web portion thereof, and a boss portion depending from said last-named flange portion and having a bore therein for reception of a bolt for securing the inclined bobbin chute to the bracket.

6. In a loom having a lay, a pitman arm for 65 driving the lay and a protector rod extending beneath, and substantially parallel to, said lay; improved swords for supporting the lay, each sword comprising a shank having a pair of laterally spaced ears thereon, an anti-friction bearing in each of said ears, a pivot shaft mounted in the bearings and spanning the distance between each pair of ears and on which the front end of the corresponding pitman arm is adapted to be secured, a protector rod bracket for each 70 shank, an end flange on each bracket, means to

removably secure said end flange against the outer surface of the corresponding shank and overlapping one of the ears of the shank, said flange having an opening therethrough coinciding with, and of greater size than, the corresponding anti-friction bearing, each protector rod bracket also comprising a substantially vertical web portion, means securing the lay to each of the web portions, a bearing holding projection extending forwardly from the lower portion 10 of each of the web portions and beneath said lay, and an anti-friction bearing mounted in

said bearing holding projection on each of the protector rod brackets for oscillatably supporting said protector rods.

JESSE B. GOODGAME.
